UNITED STATES PATENT OFFICE

LOUIE BORTKEWICZ, OF RACOON, PENNSYLVANIA

BIT-FORGING MACHINE

Application filed July 30, 1929. Serial No. 382,214.

This invention relates to a cutter-bit forging machine and consists in improvements in the mechanical elements of the machine to operate more effectively the forging dies.

In the forging of tools, such as cutter-bits for coal-mining machinery, it has been found that, if the forming dies are operated to strike a blow which is similar to a blow delivered by a hand-hammer, the grain structure of the metal of the tool is superior to that of tools formed in machines having positively operated dies which press the metal to form.

The object of the invention is to provide a machine for forging cutter-bits by a succession of blows of resiliently operated dies.

In the accompanying drawings Figure 1 is a view in top-plan elevation of the machine of my invention; Figure 2 is a view in rear elevation of the same; Figure 3 is a sectional view, taken on the plane 3-3 of Figure 2, showing in side elevation the mechanical elements which operate a forging die; and Figure 4 is a sectional view, taken on the plane 4-4 of Figure 2, showing in side elevation the elements which operate another forging die.

Referring to the drawings the numeral 1 indicates the bed of the forging machine, 20 and 2 designates frame members which support it. The feeding device 3 presents blanks through an opening 4 in the bed of the machine to a suitably formed anvil block 5, and the two heads 6 and 7, having appropriate die faces 8 and 9 respectively, reciprocate to form the cutter-bit.

As may be seen in Fig. 1 the anvil block 5 has two faces 5a and 5b which slope upwardly from the hole 4. The faces 5a and 5b lie angularly to each other, meeting in a corner 5c. In forging a bit the head 6 co-operates principally with the face 5a, and the head 7 co-operates with the face 5b.

The travel of a bit blank may be traced 45 in Figure 3. An arcuate conduit 11 is pro-

vided within the feeding device, and therein a feeding block 12 slides in accordance with the rotation of the connecting arm 13. Rotation is effected by means of the handle 14. Through an opening 15, a heated bit blank 50 is inserted to the conduit 11—obviously, the block 12 is first moved into the position indicated by the broken lines 12a. The handle 14 is then rotated to move the block and to feed the blank through the opening 4 to the 55 anvil 5, against which the heads 6 and 7 form the bit 10.

The invention has particularly to do with the means which operate the heads 6 and 7. As said, it is desirable to obtain forming 60 blows which are similar to those delivered by a manually operated hand-hammer. I have found that, by storing energy in resilient means, such as springs, the heads may be released to the forces of the stored energy to strike blows of the desired quality. In this practice I attach an arm 16 to the head 7, which slides in the way 17. This arm is pivotally mounted between the brackets 18 of the machine, and by means of the 65 pin and groove connection 19 to the head 7, oscillation of the arm will cause reciprocation of the head. It is obvious that the head and arm may be formed integrally, if an arcuate movement of the head is desired. Fixed to the arm and to the machine frame 70 is the tension spring 20, and when the arm 16 is released to the force of this spring (the spring being expanded as shown in Figure 3) it will rotate the arm and move the head 75 7 to strike a blow. The arm and head are then returned to their inoperative position 80 by positive mechanical elements.

These elements comprise a cam 21 which is fixed to the counter-shaft 22. This counter-shaft is geared at 23 to the drive shaft 24 which is suitably equipped with a belt pulley 25 and a clutch 26 to be rotated as desired. As may be seen in Figure 2 the cam has an indented surface 21a, and rota- 90

tion of the cam in the direction of the arrow will free the end 16a of the arm 16 and permit the spring to operate the die head. Continuing rotation of the shaft 22 and cam 21 brings the cam portion 21b against the end 16a and moves the arm and head back to inoperative position, where, due to the cam surface 21c, it is maintained for an appreciable interval of time—the interval necessary to permit the unobstructed operation of the die head 6.

The die head 6 slides in the way 30 between guides 31 and 32. It strikes the blank on the anvil a forming blow which is directed 15 at an angle of 90° from the movement of the head 7. An arm 33 is pivoted to the fixed standard 34, and is connected to the head 6 by means of the pin and groove arrangement 35. A spring 36 is mounted to operate 20 this arm similar to the manner in which the spring 20 operates the arm 16. By means of the helical cam 37 the end 33a of the arm 33 is released to the force of the expanded spring 36, which, of course, moves 25 the die head 6 to strike a forming blow. The cam 37, obviously, is adapted to return the arm to its initial position and to retain it there until the head 7 has operated. The particular cams, which are illustrated, 30 are of such form as to permit both of them to be affixed to the shaft 22. This is advantageous, because it permits the cams to be adjusted on a single shaft and insures a positive synchronization of the alternately 35 moving die heads.

To prevent scale from forming and remaining on the point 10a of the hot cutter bit (during the last stages of the forging operation), I have provided a tappet rod 40, shown in broken lines, having the depending member 41 to strike lightly the point of the bit. Suitable connections to the moving elements of the machine may be employed to render a vertical reciprocating 45 movement to the rod 40. Such connections may conveniently be an eccentric or cam 42 which is operatively geared at 43 to the shaft 22.

What I claim is:

50 1. In cutter-bit forging apparatus including a machine bed supported on a frame and an anvil secured to the machine bed, and an opening through such machine bed for feeding a bit blank to the anvil, which anvil includes two faces both of which slope upwardly from said opening and extend angularly to each other, the combination of a bit-forming head which is movable relatively to the anvil to and from forging 55 position against one of said anvil faces, a second bit-forming head which is movable relatively to the anvil to and from forging position against the other of said anvil faces, a head-operating arm for each bit-forming head, which operating arms pro-

ject through said machine bed and are connected one to each of said bit-forming heads, said operating arms being each pivotally secured to the machine below said bed, yielding means for each operating arm normally urging each bit-forming head into position against said anvil, and means below said bed for periodically moving each of said operating arms alternately to store energy in its associated yielding means and for periodically and alternately releasing said arm to the energy of such yielding means. 70

2. In cutter-bit forging apparatus including a machine bed supported on a frame and an anvil secured to the machine bed, and an opening through such machine bed for feeding a bit blank to the anvil, which anvil includes two faces both of which slope upwardly from said opening and extend angularly to each other, the combination of a bit-forming head which is movable relatively to the anvil to and from forging position against one of said anvil faces, a second bit-forming head which is movable relatively to the anvil to and from forging position against the other of said anvil faces, a head-operating arm for each bit-forming head, which operating arms project through said machine bed and are connected one to each of said bit-forming heads, said operating arms being each pivotally secured to the machine below said bed, and means below said bed for alternately oscillating said arms angularly about their pivotal attachment to the machine for effecting the movement of said bit-forming heads one after the other into forging position against the respective faces of said anvil. 90

3. In cutter-bit forging apparatus including a machine bed supported on a frame and an anvil secured to the machine bed, and an opening through such machine bed for feeding a bit blank to the anvil, which anvil includes two faces both of which slope upwardly from said opening and extend angularly to each other, the combination of a bit-forming head which is movable relatively to the anvil to and from forging position against one of said anvil faces, a second bit-forming head which is movable relatively to the anvil to and from forging position against the other of said anvil faces, ways secured to said machine bed for each head, and a head operating arm for each of said heads, which operating arms project through said machine bed and are connected one to each of said heads, said operating arms being each pivotally secured to the machine below said bed, and means below said bed for oscillating alternately said operating arms and causing said heads to slide each in its associated way successively into forging position against said anvil. 105

4. In a bit-forging machine including an 130

anvil and means for feeding a bit blank thereto, the combination of a bit-forming head reciprocatory to and from forging position upon said anvil, a tappet rod, a point-
5 tapping member associated with said rod, and means for reciprocating said rod and its associated tapping member during the forging of a cutter bit, whereby, the immediate point of the bit being forged is sub-
10 jected to tapping blows which are effective to work the metal of said bit point and to remove such scale as forms on said point.

In testimony whereof I have hereunto set my hand.
